Inventor:

Christian August Carl Peschardt

By *June Daniels, her*
Attorney.

UNITED STATES PATENT OFFICE.

CHRISTIAN AUGUST CARL PESCHARDT, OF AALBORG, DENMARK.

COMBINED WATER CONTAINER AND BASIN.

Application filed April 20, 1922. Serial No. 555,702.

To all whom it may concern:

Be it known that I, CHRISTIAN AUGUST CARL PESCHARDT, subject of the King of Denmark, residing at Aalborg, Denmark, 5 have invented certain new and useful Improvements in Combined Water Containers and Basins, of which the following is a specification.

This invention relates to a water container 10 and basin which may, as a combined whole, be arranged in the tool boxes or the like of automobiles or the like wherein it will occupy a relatively small space only.

When driving motor cars it happens at 15 times that, on account of mishap or for other reasons it will be necessary on the open road to make small repairs, to inspect the motor, to inflate the tyres, etc. It is obvious that such repairs, etc., cannot be 20 made without the person attending to them getting dirty to a considerable degree, especially on his hands, and it is often—especially if he be a gentleman driver—very inconvenient for him not to be able to 25 wash himself before resuming the driving.

Towel and soap can always easily be carried in the car, whereas difficulties arise as regards basin and water jug containing water. Of course, an ordinary basin may 30 be wrapped and put into the car, and some container that is capable of being tightly closed may be filled with water and put into the car. Such an arrangement is, however, inconvenient and a rational arrangement is 35 brought about only if the outfit of the car comprises a basin and a water jug of such a special construction and fitting that said parts form a, so to say, regulation part of the contents of the tool and outfit box without occupying too much space or requiring 40 a space of a special shape in the box.

The present invention relates to a combined water container and basin adapted for the special purpose in view and which is, 45 therefore, meant to be used especially in connection with automobiles. It must, however, be understood that the invention is not limited to this special use, but that it may be used under other conditions, it being useful everywhere where it is important 50 that a certain quantity of water and a basin can be carried without taking up too much space.

A form of execution of the invention is shown on the drawing, where 55

Fig. 1 is a perspective view of a basin,

Fig. 2 is a perspective view of a corresponding water jug.

Fig. 3 shows the water container and the basin, the former inside the latter, 60

Fig. 4 a perspective view of the water container showing how the spout may be arranged.

In the construction shown on the drawing the basin 1 and the water container 2 are 65

in the shape of flat-bottomed troughs and the water container will, when introduced into the basin 1 completely fill the inner space of the latter and will project outside same only along its flanged upper edge 3, 70 the said flange constituting a means whereby it can easily be lifted out of the basin when it is to be used. One corner of the flat top or cover of the water container is depressed or recessed so that the height of 75 the water container is at that point somewhat less than at any other point. On the bottom wall of this depressed part of the container is disposed a short spout 4 which can be tightly closed by means of a screw 80 lid 5 provided with a gasket or a packing made, for example, of rubber; and it is to be observed that this spout does not project above the top wall or cover of the container but is, on the contrary, disposed 85 wholly within the confines of the depression or recess, so that it will not interfere with the placing of tools or other articles on top of the aforesaid cover when the device is located within the tool box. 90

The form of execution shown in the drawing is simple and suitable to the purpose, but it is clear that it may be altered in many ways without departing from the principle of the invention. For 95 instance, the basin and the water container may be of any other shape if only the two parts fit into one another, and the flange 3 may be replaced by a couple of handles, or by one handle or a ring or the like arranged 100 in a recess in the surface of the container.

The basin and the container may be made of metal or any other suitable material.

I claim:

1. A combination article, comprising a 105 basin; and a removable water container

conformably fitting therein and having a flat top or cover which is depressed at one point to provide a space or recess, the bottom wall of said recess having secured to it 5 a pouring spout which is provided with a closure and disposed wholly within the confines of the recess.

2. A combination article, comprising a flat-bottomed basin; and a removable water 10 container conformably fitting therein and

having a flat top or cover which is disposed substantially in the plane of the upper edge of the basin and which is depressed at one point to provide a space or recess, the bottom wall of said recess having secured to it 15 a pouring spout which is provided with a closure and disposed wholly within the confines of the recess.

In testimony whereof I affix my signature.
CHRISTIAN AUGUST CARL PESCHARDT.
